PAIR OF SUNGLASSES

Albert C. Petitto, Hudson, Mass., assignor to Foster Grant Co., Inc., Leominster, Mass., a corporation of Delaware

Filed Mar. 21, 1961, Ser. No. 64,422

Term of patent 14 years

(Cl. D57—1)

FIG. 1

The rear not shown is substantially plain and conventional.

The characteristic features of my design for the sunglasses disclosed resides in the ornamentation applied to the front face of the spectacles as shown.

I claim:

The ornamental design for a pair of sunglasses, substantially as shown and described.
